ICE SPOON

Gustav Mårten Blomqvist, Stockholm, Sweden,
assignor, by mesne assignments, to Servel, Inc.,
New York, N. Y., a corporation of Delaware

Application May 12, 1937, Serial No. 142,161
In Germany June 9, 1936

1 Claim. (Cl. 62—108.5)

My invention relates to ice spoons for use in household refrigerators, and it is an object to provide such an ice spoon which is insertable in a freezing compartment of a refrigerator to produce ice, and thereafter can be used immediately by placing the spoon and its frozen contents into a glass containing liquid to be cooled.

In cooling liquid in glasses it is generally the practice to take out an ice tray from the freezing compartment of a refrigerator and thereafter remove the grid and ice cubes from the tray. Even when only a few cubes are to be used, the tray must be taken out of the freezing compartment and the entire grid removed from the tray. This not only is time consuming but involves the loss of considerable ice due to melting thereof when the tray is removed from the freezing compartment and only a few ice cubes are used.

In accordance with my invention I provide an ice spoon for producing ice, the spoon being shaped and formed so that it will readily stand in an upright position on a supporting surface in a freezing compartment and also provide a good heat conductive path for removal of heat through the bottom of the spoon and the supporting surface. When the water in a spoon is frozen, the spoon can be used immediately to stir liquid to be cooled without any inconvenience of removing the ice from the spoon.

The invention, together with the objects and advantages thereof, will be apparent from the following description taken in conjunction with the accompanying drawing forming a part of this specification, and of which Fig. 1 is a view, partly in section, of a cooling element of a refrigerator in which ice spoons embodying the invention are disposed; Fig. 2 is a top plan view of one of the ice spoons shown in Fig. 1; Fig. 3 is a longitudinal sectional view taken on line 3—3 of Fig. 2; and Fig. 4 is a sectional view of the handle of the ice spoon taken on line 4—4 of Fig. 3.

Referring to Fig. 1, an evaporator or cooling element 10 of a household refrigerator 11 is refrigerated in any suitable manner. The cooling element 10 is provided with a plurality of ice freezing compartments 12 in one of which are disposed two ice spoons 14.

In accordance with my invention each ice spoon 14 is formed with a flat bottom 15 in order to provide good thermal contact with the supporting shelf 16. The walls 17 of the spoon body are preferably perpendicular to or slant outwardly from the flat bottom 15 so that a maximum quantity of ice can be produced in each spoon. The

bottom corners of the spoon body are preferably rounded, as indicated at 18.

The spoon 14 is provided with a handle 19 which extends horizontally from the top edge of one of the side walls 17. The outer end of the handle 19 is curved or bent with the relatively broad extreme end 20 in the same horizontal plane as the flat bottom 15. The extreme end 20 of the handle 19 rests on the shelf 16, so that the spoon will readily remain in a stable upright position with the entire 10 bottom 15 contacting the shelf.

The handle 19 is preferably made sufficiently rigid to resist bending or flexing when the spoon 14 is removed from the ice freezing compartment 12. This may be accomplished by making the 15 handle U-shaped in section, as shown in Fig. 4. If desired, the handle 19 may be given any other shape, such as a T-shaped section, for example, to resist flexing or bending when force is applied to the outer end thereof.

In order that several spoons 14 may be inserted into a single ice freezing compartment to efficiently utilize the space, at least a part of the handle 19 is higher than the walls 17 of the spoon, so that the body of another spoon can be inserted 25 under the handle. As shown in Fig. 1, the greater portion of the handles 19 of the spoons 14 are at a higher level than the walls 17 so that the body of one spoon can be inserted into the compartment 12 under the handle 19 of another spoon.

In using spoons of the type just described, several spoons are filled with water or other matter to be frozen and inserted in the freezing compartment 12. With the spoons 14 positioned in the cooling element 10, heat is removed from the 35 flat bottoms 15 through the shelf 16, due to the production of cold by the cooling element, whereby ice is produced in the spoons. When it is desired to use one of the spoons 14, the curved outer end of the handle 19 is raised to break the ice bond 40 that may be formed between the flat bottom 15 and the shelf 16. Due to the rigidity of the handle 19, the lifting force is effectively transmitted to the body of the spoon. With the spoon removed from the freezing compartment, it can be 45 inserted immediately into a glass full of liquid to be cooled without any inconvenience whatsoever to the user. Since the spoon may be placed into the liquid directly after its removal from the ice freezing compartment, all of the ice is effectively 50 used. In addition, cooling of the liquid is effected by the spoon itself which is at a freezing temperature.

If desired, the spoons may be used for purposes other than to produce ice for cooling liquid. For 55

example, the spoons may be employed to cool a beverage directly as well as to provide individual servings of ice cream.

Although a particular embodiment of the invention has been shown and described, it will be apparent that modifications and changes may be made without departing from the spirit and scope of the invention.

What is claimed is:

- 10 A spoon for use in a household refrigerator adapted to contain matter to be frozen and including a body portion having an essentially flat bottom to provide good thermal contact with a supporting surface of a freezing compartment,
- 15 said body portion having a side wall about the

periphery of said flat bottom, and a handle extending from said side wall having the outer end thereof curved or bent to rest on the supporting surface to provide a thermal conductive path between said side wall and the supporting surface 5 and also an additional region of support for said spoon to assist and maintain said spoon in a stable position on the supporting surface, at least a part of said handle being sufficiently high and of sufficient length to permit one other similar spoon to 10 be inserted into the freezing compartment by moving said body portion thereof under said handle whereby said spoons are disposed in crisscross relation.
